UNITED STATES PATENT OFFICE.

STEPHEN L. MERSHON, OF LLANERCH, PENNSYLVANIA.

IGNITING DEVICE FOR FUEL BURNERS.

Application filed January 17, 1923. Serial No. 613,113.

To all whom it may concern:

Be it known that I, STEPHEN L. MERSHON, a citizen of the United States, and a resident of Llanerch, in the county of Delaware and State of Pennsylvania, have invented certain new and useful Improvements in Igniting Devices for Fuel Burners, of which the following is a specification.

My invention relates to devices for igniting fuel projected into a pot or burner in the form of a very fine spray, and particularly to those burners wherein the fuel employed is a heavy oil which does not readily ignite at low temperatures. My invention 10 has particular reference to those oil fuel burners which are used for domestic heating purposes, although my invention may be readily used without substantial change for igniting heavy oil burners which are used in 15 power plants, or in any place where a spray of fuel having a high ignition point is automatically lighted and extinguished, and may at times remain extinguished long enough to 20 allow the pot or burner to become quite cold. 25 When a liquid fuel burner has been extinguished for some time, and the burner or pot is cold, great difficulty is frequently experienced in igniting the cold fuel projected into the burner as a fine spray of 30 heavy cold oil. The ignition point of such oil is relatively high, that is to say, it must be heated considerably before it readily ignites or burns, and although burners may be provided with a pilot light by means of 35 which a small flame is kept continually burning within the pot or burner, such pilot light will not, under the conditions stated, accomplish the purpose for which it is intended, that is to say, it will not ignite 40 the spray of heavy fuel.

Fuel is sprayed into the burner or pot at a relatively high velocity in minute particles by means of an air blast. It may be therefore that the particles are driven 45 through the flame of the pilot light so rapidly that the temperature thereof is not raised to the ignition point. The particles do not probably remain in the flame long enough to become heated to the ignition 50 point of the oil. But whatever may be the cause the result is that the pilot light will not ignite the fuel, or rather cannot be depended upon to ignite the fuel. It is generally necessary to put paper or kindling

into the burner, before projecting sprayed 55 fuel into the burner, in order to insure the ignition of the fuel when the burner is cold. It will also be obvious that it will be uneconomical and unpractical to supply the pilot light with enough illuminating gas 60 to continually maintain a flame great enough to ignite a cold sprayed fuel.

The object of my invention is to provide an oil burner of the type above described with a device which will insure the immediate 65 ignition of a cold oil fuel sprayed into a cold burner, provided with the ordinary small pilot light flame kept burning therein.

Referring to the drawing forming a part of this specification, and in which the same 70 reference characters are employed throughout the various views to designate the same parts, Fig. 1 is a plan view of an oil burner designed for domestic purposes located in the fire-box of a domestic boiler or water-heater, the part of the boiler or heater structure immediately above the burner being shown in section on the line 1—1 of Fig. 2; and Fig. 2 is a vertical sectional view of the 75 boiler or heater structure, and through the pot or burner of an oil burning apparatus, showing my invention applied thereto, the atomizer or spraying device being conveniently shown in side elevation.

In the drawings a heavy oil burner is 85 shown. In this burner a suitable fan (not shown) is mounted in the fan casing 1 and this fan is driven by a shaft 2 preferably directly coupled to an electric motor (not shown). When the burner is not being used 90 the current supplying the energy to the electric motor is automatically cut off so that the motor and fan are not in motion, and when the temperature of the room or space being heated by the heater falls below a 95 certain predetermined temperature, the current supplying energy to the motor is automatically closed by a thermostatic regulator, and the motor is driven, the fan revolved and a heavy liquid fuel is pumped or admitted by the pipe 3 to the nozzle 4 of the atomizer, whence the fuel is projected into the pot or burner 5 as a very fine spray intimately mixed with air. A supplemental air-pipe 6 may also communicate at one end 100 with the fan casing 1 and at its other end open tangentially into the pot 5 through the opening 7 for the purpose of giving a whirl-

ing or circular motion to the atomized fuel in the pot. In some burners, however, this supplemental air-pipe may be omitted and all the air that is supplied to the burner enters with the fuel through the nozzle 4. My invention is equally adaptable to both types of burners.

Within the pot 5 is a pilot light 8. Illuminating gas is supplied to the burner of the 10 pilot light and a small flame is kept continually burning within the pot 5.

So far, I have described a heavy fuel burner and pilot light in which my invention may be used but my invention is not to 15 be construed as limited to any particular form or type of burner other than one in which a fuel is projected as a fine spray into a pot which may at times be cold and wherein a pilot light is kept continually burning.

20 In such constructions it is very difficult to ignite the atomized fuel in starting the burner when the pot is cold. When the cold sprayed fuel is projected into the pot, the heat from the weak pilot light is insufficient 25 to ignite it and, indeed, care has to be taken to make sure that the draft caused by the rush of the incoming fuel does not in fact extinguish the pilot light.

I have discovered, however, that if I suspend or mount a relatively small body of 30 spherical or other suitable shape and preferably composed of heat conductive material, in such proximity to the flame of a relatively small pilot light, that the said light 35 keeps the ball or body relatively hot, an incoming cold charge of sprayed heavy fuel will invariably and almost immediately ignite. I am not certain as to what is the exact cause or reason for this immediate 40 ignition. It may be because the relatively large surface of the relatively warm or hot body serves to quickly raise the temperature of all the particles of fuel, whirling around in the pot, to a point where the pilot flame 45 will ignite them; or it may be that certain of the minute particles of heavy fuel are projected upon and remain on the surface of the relatively warm body, and are retained there long enough to absorb heat from the warm 50 ball or body sufficient to raise the temperature thereof up to a point where the weak pilot light flame will ignite them and that the other particles, whirling around within the pot, are ignited by the combustion of the 55 particles on the ball or body; or it may be that the liquid sprayed upon the spherical body forms drops which run down over the ball to the under side thereof, over or in the flame of the pilot light, and remain there long enough to ignite, and that the heat of the burning drop or drops is communicated 60 to particles whirling around within the pot to ignite them. I am inclined to think that possibly the latter theory may be the most nearly correct one, but the ignition is so

rapid that I am not yet certain as to just what action does take place within the pot, and I therefore do not wish to be construed as limiting my device to any particular mode of operation.

70 This ball or hot body 9 may be mounted at the end of a rod 10, passing through a horizontal transverse bar 11 resting across the top of the mouth of the burner or pot 5, and having a nut 12 threaded over the upper end thereof for the purpose of adjusting the distance between the ball 9 and the pilot light burner 8. It is obvious, however, that this ball 9 may be suspended over the flame of the pilot light 8 in any suitable manner 75 so long as it is in such a position as to be kept heated by the flame of the pilot light, and be in the path of the fuel which is projected into the pot 5 from the atomizer or nozzle 4. It is believed that the operation 80 of my device will now be apparent. Assuming the pot 5 to be cold, the fan in the fan casing 1 to be not in motion and the flame from the pilot burner 8 to be continually ignited and in such a position under the ball 9 as to keep the ball 9 relatively hot, and assuming now that the burner is to be 85 ignited, motion is communicated to the fan in the fan casing 1 and finely divided or atomized liquid fuel is projected by the air 90 blast supplied by the fan, into the pot 5 through the nozzle 4. Some of the particles of ignited fuel may strike squarely against the hot sphere or body 9; may almost immediately ignite, and their combustion may 95 serve to so raise the temperature of the other particles in the pot that they also almost immediately ignite, and the pot and in fact, the space above the burner will be filled with 100 flaming fuel. Or, if the other be the correct 105 theory, the cold small particles whirling around within the pot as delivered from the nozzle strike against the hot ball or body 9 and the temperature of the whole whirling 110 mass of fuel is rapidly raised to such a temperature that the feeble flame from the pilot light almost immediately ignites them; or it may be that drops of liquid, collecting on the ball, run down to a point over or in the 115 flame, and burning there, seem to communicate the heat of their combustion to the incoming particles to ignite them.

120 But irrespective of what may be the controlling reason for the immediate ignition of the atomized fuel, I have discovered that when a ball of iron, or other suitable heat-conductive substance, is suspended over the feeble pilot light of a heavy oil burning burner and maintained hot thereby, the incoming cold fuel will ignite within a very 125 few seconds.

The material of which this heated body is composed is preferably iron, although it may be composed of any suitable material which can be readily heated by the flame of a pilot 130

light and which will not disintegrate under the high heat developed by the combustion of the atomized fuel when the burner is being operated.

5 It is also to be noted that the ball or mass of material forming the igniter should not be so attached or connected to the metal of the burner itself that heat will be conducted away from the ball to the burner. Some 10 small metallic connection, such as the bolt or rod 10, or a chain, may be used because such a relatively small metal connection between the ball 9 and the pot 5 will not rapidly conduct heat away from the ball. To 15 this extent then, the ball 9 may be said to be substantially air-insulated or heat-insulated from the pot or burner 5.

The size and shape of the mass which is suspended or mounted above the pilot may 20 be varied in wide limits. I prefer, however, to use a ball, or spheroid, because thereon any liquid which might collect and run down the sides thereof will be conducted to a single point, i. e., the lowest point of the 25 ball, into the flame of the pilot-light, where it may be rapidly heated and ignited by the pilot-light.

Having thus described my invention, what 30 I claim and desire to protect by Letters Patent of the United States, is:

1. In a burner for atomized fuel comprising a pot or burner, means to project an atomized fuel into said burner and a pilot light in said burner, the combination there- 35 with of a body of material which will not melt or disintegrate under the heat developed by the combustion of said atomized fuel, mounted within said burner and maintained relatively hot by said pilot light

whenever atomized fuel is not being burned 40 in said burner.

2. In a burner for atomized fuel comprising a pot or burner, means to project an atomized fuel into said burner and a pilot light in said burner, the combination there- 45 with of a body of material which will not melt or disintegrate under the heat developed by the combustion of said atomized fuel, mounted within said burner and over 50 or in the flame of said pilot light and maintained relatively hot by said pilot light whenever atomized fuel is not being burned in said burner.

3. An igniter for burners adapted to consume an atomized fuel projected by an air 55 blast into a pot or burner provided with a pilot light, comprising a body of material which will not melt or disintegrate under the heat developed by the combustion of said atomized fuel, mounted within and heat 60 insulated from said burner and maintained relatively hot by said pilot light whenever atomized fuel is not being burned within said burner.

4. In a burner for atomized fuel comprising a pot or burner, means to project an atomized fuel into said burner and a pilot light in said burner, the combination there- 65 with of a metal ball mounted within and substantially air-insulated from, and main- 70 tained in heated condition by said pilot light whenever atomized fuel is not being burned within said burner.

In witness whereof, I have hereunto set my hand this sixteenth day of January, 75 1923.

STEPHEN L. MERSHON.
